UNITED STATES PATENT OFFICE

CLARENCE L. FORETICH, OF WARREN, ARKANSAS

DESIGN FOR A DISPLAY STAND

Application filed December 3, 1931. Serial No. 41,952. Term of patent 14 years.

To all whom it may concern:

Be it known that I, CLARENCE L. FORETICH, a citizen of the United States of America, residing at Warren, in the county of Bradley and State of Arkansas, have invented a new, original, and ornamental Design for Display Stands, of which the following is a specification, reference being had to the accompanying drawings, forming part thereof.

Figure 1 is a perspective view of a display stand, showing my new design,

Figure 2 is a view of the stand showing the pedestal in section and the shelves in plan;

Figure 3 is a perspective view of one of the units; and

Figure 4 is a view in side elevation showing one of the units and its support.

I claim:

The ornamental design for a display stand, as shown.

CLARENCE L. FORETICH.
